UNITED STATES PATENT OFFICE.

WILLIAM A. LORENZ, OF HARTFORD, CONNECTICUT.

DESIGN FOR A JAR.

SPECIFICATION forming part of Design No. 33,417, dated October 23, 1900.

Application filed June 2, 1900. Serial No. 18,903. Term of patent 14 years.

To all whom it may concern:

Be it known that I, WILLIAM A. LORENZ, a citizen of the United States, residing at Hartford, in the county of Hartford and State of Connecticut, have invented a new and original Design for a Jar, of which the following is a specification, reference being had to the accompanying drawings, forming part thereof.

Figure 1 of the drawings is a plan view, 10 and Fig. 2 a side view, of a jar or receptacle embodying my design.

The substantially-cylindrical body 10 of the jar merges toward its upper end into a slightly-tapering or conical portion interrupted by an 15 annular recess 12, which separates the conical portion into two zones 11 and 13, the latter of which is narrow and substantially cy-

lindrical. The recess 12 is substantially semi-circular, its upper and lower surfaces forming definite angles with the surfaces of the 20 zones 11 and 13.

Having described my invention, what I claim as new, and desire to obtain by Letters Patent, is—

The design for a jar, as herein shown and 25 described.

In testimony whereof I have signed my name to this specification, in the presence of two subscribing witnesses, this 31st day of May, 1900.

WILLIAM A. LORENZ.
